UNITED STATES PATENT OFFICE

2,361,364

CAP-FEEDING APPARATUS

William D. Bell, Columbus, Ohio, assignor to
Anchor Hocking Glass Corporation, Lan-
caster, Ohio, a corporation of Delaware

Original application September 20, 1940, Serial
No. 357,586. Divided and this application De-
cember 2, 1941, Serial No. 421,335

3 Claims. (Cl. 226—88.1)

My invention relates to a cap-feeding apparatus. It has to do, more particularly, with a cap-feeding apparatus adapted to be associated with a sealing machine which seals the cap on a container and, preferably, displaces the air from the head space of the container before the sealing operation.

This application is a division of my co-pending application S. N. 357,586; an Apparatus for sealing containers, filed Sept. 20, 1940, now Patent No. 2,296,013, issued September 15, 1942.

One of the objects of my invention is to provide a cap-feeding apparatus which is very simple in structure and embodies a minimum number of moving parts.

Another object of my invention is to provide a cap feed which is of such a nature that it will receive a stack of caps and will feed the caps one-by-one to the sealing mechanism of the sealing machine.

Another object of my invention is to provide a cap-feeding apparatus of the type indicated which is of such a nature that the lowermost cap in the stack will be positively separated from the stack at the proper time.

Another object of my invention is to provide a cap-feeding device of the type indicated in the preceding paragraph having simple means for feeding the released cap into association with the sealing mechanism of the machine.

In its preferred form, my invention contemplates the provision of a cap-feeding unit embodying an inclined magazine for receiving a stack of nested caps. This magazine is mainly of semi-cylindrical form except at its lower end which is of cylindrical form. The lower end is tilted upwardly from the horizontal. At the upper and forward side of the tilted lower end of the magazine a movable feed control member is provided for supporting the forward edge of the lowermost cap while at the lower and rear side of the tilted lower end of the magazine a stationary support is provided for said cap at a point diametrically opposed to the point where the feed control member is provided. The feed control member is the only movable part for controlling the feed of caps from the stack. This member takes the form of a rotatable vertically disposed substantially disk-like member disposed in a plane at right angles to the plane of the lowermost cap. The feed control member is provided with a notched portion and a finger thereabove. The lowermost cap normally rests on the bottom of the notched portion but when the cap feed control member is rotated, the finger above the notch

passes between the lowermost cap and the cap next above and positively separates these caps while supporting the stack of caps above the lowermost cap. When the feed control member is returned to its original position, the cap which has become the lowermost cap will rest on the bottom of the notched portion. The rear and lower edge of the lowermost cap supports most of the weight of the stack of caps which tends to keep the lowermost cap in position where it will be engaged by a pawl carried by a slide, substantially at the same time it is released from the stack which serves to feed the cap into association with the sealing mechanism.

15 The preferred embodiment of my invention is illustrated in the accompanying drawings wherein similar characters of reference designate corresponding parts and wherein:

Figure 1 is a vertical sectional view of the sealing mechanism and associated cap feed.

20 Figure 2 is a vertical sectional view showing the initial stage of releasing a closure from the closure magazine.

Figure 3 is a vertical sectional view of the same 25 cap feed showing the cap immediately after release and the manner of upholding the remaining caps.

With reference to the drawings, I have illustrated an automatically operated capping machine of a type in which my invention has been embodied.

The closure holding means and its associated delivery mechanism will now be described in detail. Bolted to the upper surface of platform 3 by means of bolts 27 is the cap holder or magazine generally designated as 1. The cap holder 1 takes the form of a base 29 supporting integrally therewith and in a slightly inclined position a semi-cylindrical member which is adapted to hold a stack of caps that can be readily laid therein. At its bottom, a small portion of this cap holder is completely cylindrical as at 30. This construction is clearly shown in Figure 1. Since the whole stack of caps is maintained in an inclined position, it will be seen in Figure 1 that the weight of this stack will rest largely on two edges of the lowermost cap. Thus, the rear edge 31 of the lowermost cap rests on a depressed surface 32 of platform 3 having formed therein a slot 32a which is formed substantially throughout the length of such depressed surface. This depressed surface 32 extends from the bottom of the cap holder 1 to the cap sealing head. The forward end of the depressed surface 32 which is 55 adjacent to the sealing head supports the tracks

26 which form continuations thereof. The forward edge 34 of the lowermost cap rests on the lower surface 35 of a notch 36 formed in a disc 37. It will be seen that the notch 36 and the disc 37 are so located and of such form that when the disc 37 is oscillated it will have an escapement-like action, or in other words, the upper surface or claw-like member 38 of notch 36 in the disc 37 will separate the lowermost cap from the stack and positively force it downwardly and allow it to drop in the longitudinal depressed surface 32. While the lowermost cap is being forced downwardly by the claw-like member, the surface 39 of the disc 37 will support the stack of caps as shown in Figures 2 and 3. Upon the release of the lowermost cap, the disc 37 is rotated in the opposite direction until the forward edge 34 of the cap which is now lowermost rests upon the surface 35 of the notch 36 and the cap which is now lowermost is now in a position ready for release from the cap holder 7.

The disc 37 is mounted for its escapement-like motion on one end of a shaft 40. On the other end of the shaft 40 is rigidly mounted an arm 41 which extends upwardly. This arm 41 has a pin and yoke connection 42 with the downwardly extending arm 43. The other end of the arm 43 is rigidly fastened to one end of the driving rod 13. It is understood, that when the rod 13 is driven to the left in Figure 1, it causes the arm 43 to rotate the disc 37 a certain number of degrees through the medium of its supporting shaft and associated arm 41.

When a cap is dropped into the depression 32 it is in front of a pawl 44. Pawl 44 is carried by cross member 44a whose ends are connected to links 45. When suitably actuated said pawl 44 is adapted to draw the cap from its position beneath the cap magazine onto the cap-holding hinges 22. The mechanism accomplishing this result will now be described in detail. The ends of the links 45 opposite to those at which the cross member 44a is attached are connected to the lower ends of levers 46. The upper ends of levers 46 are rigidly attached as at 47 to a horizontal shaft 48, said shaft 48 being rotatably mounted in the walls of the sealing unit 6. The levers 46 are attached to the rotatable shaft 48 at a point outside of the walls of the sealing unit. Suitably mounted on the shaft 48 is the torsion spring 48c. This spring normally moves the pawl and a cap forward to sealing position.

In the center of the shaft 48 is rigidly attached a downwardly extending trigger or finger 48a whose lower end extends into a notch 48b in the rod 13. This trigger is so constructed that when the rod 13 is driven forward the shaft 48 is caused to rotate and thereby actuate the pawl 44 through the medium of its associated mechanism. When the rod 13 has moved far enough to the right in its return stroke, the trigger 48a reaches a position where its downward swinging action will not be prohibited, as it formerly was by the surface of the rod 13. Thus, when the trigger reaches this position, the torsion spring 48c rotates the shaft 48 and forces the trigger into notch 48b. It will be seen that the spring 48c rotating the shaft 48 and its associated mechanism will deliver the closure to the sealing head.

The means for driving the rod 13 which causes a cap to be delivered to sealing position and which causes the sealing head to descend and seal the cap on the jar will now be described. The driving rod 13 is driven by an ordinary type of piston as in a combustion engine. The cylinder itself may

be designated by the numeral 49 and it has operatively disposed therein a piston 50. The piston 50 is connected to the rod 13 by any ordinary means as at 51. In the head of the cylinder 49 is disposed a spark plug 52 for ignition of the gas which may be admitted through the port 53. The gas port 53 is connected through a gas line 62 to a suitable gas pump. At the end of the cylinder where the forward stroke of the piston 50 terminates is located a port 54. In the upper inside surface of the cylinder 49 is located a channel 54b which enables the air admitted through the port 54 when the piston is in firing position to be passed from behind the piston 50 when said piston has completed its stroke to the left into the space before the piston preparatory to compression.

The piston itself has on its explosion surface a baffle 55. It will be seen that this baffle 55 will cause the air coming through the channel 54b to be more or less deflected and spread into the explosion or combustion chamber for a more uniform mixture of the air with the gas, said air and gas, of course, being subject to slight compression preparatory to combustion by the returning stroke of the piston. Mounted on the rod 13 in front of the piston is a spring 56 which is for the purpose of initiating the return stroke of the piston. The relation of the piston to the air port at the limit of its forward stroke may be seen in dotted lines in Figure 1.

It will be apparent from the above description that I have provided a cap-feeding apparatus having many advantages. The means for feeding the caps from the magazine is extremely simple embodying one moving part only. Furthermore, this means will positively separate the lowermost cap from the stack even if the lowermost cap tends to stick to the adjacent caps. The weight of the stack of caps serves to maintain the lowermost cap in position to be engaged by the pawl of the slide which feeds the cap into position beneath the sealing head. At the sealing head, the cap is effectively held in position, for the sealing operation, by the hinged flaps.

Various other advantages will be apparent from the preceding description, the drawings and the following claims.

Having thus described my invention, what I claim is:

1. A cap-feeding unit comprising a magazine for a stack of caps, said magazine being of cylindrical form and being inclined from the vertical so that the caps will be disposed in a position inclined from the horizontal, a depressed surface for supporting the one edge of the lowermost cap in the stack, separate means for supporting the opposite edge of said cap, said means comprising an oscillatable disk-like member having a notch formed therein and a wall portion defining one side of said notch upon which the said opposite edge of the lowermost cap in the stack normally rests, a claw-like finger portion located at the opposite side of the notch and providing an opposed wall portion at that side thereof, said finger portion being adapted to be projected between the lowermost cap and the cap next above upon rotation of said disk, means for rotating said disk to transfer the lowermost cap to said depressed surface, and means for supporting the caps above said lowermost cap during the rotation of said disk, said last-named means comprising the peripheral portion of said disk in the region above said finger.
2. A structure according to claim 1 wherein said

depressed supporting surface has a longitudinal slot formed therein and a yieldable pawl adapted to reciprocate in said slot to engage the discharged cap disposed on the said surface and move it to another position.

3. A structure according to claim 1 wherein a reciprocable slide is provided beneath the cap re-

ceiving and supporting surface, said slide comprising a pawl yieldable when moved past the lower edge of the lowermost cap in one direction but engageable with said edge upon movement in the opposite direction to position the cap at another location.
